TRAIN-CONTROL SYSTEM

Application filed June 16, 1921. Serial No. 477,867.

This invention relates to a train control system in which devices on the track controlled by the condition of the block, operate devices on the train which indicate when the track is clear or blocked and operate certain devices 5 for controlling the train when the track is blocked and has for an object to secure these or other results from effects communicated inductively between the track devices and the locomotive apparatus and also has for an object to secure these results without the use of permanent magnets either on the track or on the locomotive. This invention also has for an object a means for obtaining a variety of 10 effects on the locomotive apparatus by energizing the track device with currents differing in phase relation, producing a poly-phase operation. These and other objects will be more particularly understood by referring to 15 the following specification and accompanying drawings in which Fig. 1 shows a diagram of an application of my system to a locomotive and the relation of the locomotive devices to the track device, Fig. 2 is a side elevation of 20 the track device, Fig. 3 is a plan of the track wiring, Fig. 4 shows another arrangement of the locomotive wiring using poly-phase current for obtaining the effects on the locomotive from the track, Fig. 5 is a track wiring 25 plan arranged for operating the system as illustrated in Fig. 4, Fig. 6 is a modification of the locomotive wiring and Figs. 6^a and 6^b are 30 details.

This invention includes a track device made 35 in the form of an elongated track magnet having a plurality of coils which energize elongated pole pieces either by direct or alternating current. The illustrations, however, show the application of the system with alternating current only. The track device is herein referred to as a ramp. This, however, does not imply that mechanical contact between the locomotive apparatus and the track device is essential for the working of the system, 40 the term "ramp" being used herein as a convenient designation for the track device.

The locomotive device consists of an inductive shoe responsive to the track device or ramp. This shoe consists of two outer members or magnetic yokes with pole pieces sus-

pended so as to pass over the poles of the ramp and responsive to the alternating current in the ramp to energize an A. C. relay for the purpose of communicating a proceed signal to the locomotive apparatus. Located between the aforementioned outer members is placed another shoe at right angles to these members and having a pair of pole pieces influenced by one or more poles of the ramp. This shoe herein referred to as the transformer shoe, includes the magnetic circuit of a transformer having a primary winding which is permanently connected in circuit with a source of alternating current on the locomotive and which under normal conditions, maintains the proceed signal established from the A. C. members. As soon, however, as this shoe engages a plate of the ramp the reluctance of the air gap between the pole pieces is thereby greatly reduced and a direct current winding 50 on these pole pieces forces an increasing D. C. flux through the core of the transformer, thereby saturating this core with the result that the secondary of the transformer is substantially deenergized and the A. C. relays 55 are deenergized and remain deenergized while this shoe is in engagement with the ramp unless other circuits are established which energize these relays. This effect provides a condition in which the A. C. shoes 60 responding to the alternating current in the track ramp communicate a proceed signal to the locomotive, thereby canceling the effect of the transformer shoe engaging the ramp to establish a stop signal and when the A. C. 65 energy is absent in the track ramp, the transformer shoe becomes effective to establish a stop signal and operate the speed control apparatus.

Speed control is obtained by varying the 70 length of the track ramps in combination with a time element device operated by the transformer shoe on the locomotive which operates within a predetermined time interval and another device which operates during the transit of the transformer shoe over the ramp. The latter device responds to the entire time in which the transformer shoe is on the ramp while the time element device 75 releases after a given time interval. The ar- 80

angement is such that if a train passes over a ramp of a given length below a predetermined speed, the transformer shoe will engage the ramp for a time greater than the time interval of said device which thereby operates and energizes a stick relay which prevents the application of the brakes and on the other hand if the speed of the train is above a predetermined limit, the time element device does not operate and the former device having operated and released the stick relay, the brake application is made immediately that the transformer shoe is disengaged from the ramp and it remains set until manually released.

The arrangement in Figs. 4 and 5 is modified to show a system controlling over two blocks and giving an indication of stop, caution and clear on the locomotive obtained from a ramp energized by two independent sets of coils which differ in phase from each other and thereby operate a poly-phase relay on the locomotive according to the phase relation of the track apparatus. The term "shoes" herein referred to, relates to the magnetic yokes of the locomotive devices which come under the magnetic influence of the track ramp and may be arranged either to make contact with the ramp or to pass over the ramps without making contact.

Referring to the drawings, 11 represents the track rails and 12 represents the ramps, 13 is a wooden support for the laminated ramp poles 14 and 15 having the laminated cores 16 spaced at intervals and upon which the coils 17 are placed. In Fig. 3, 21 represents a track relay energized by a transformer 22 in accordance with the standard type of track circuit. 23 and 24 are a transmission line energized from the transformer 25. The coils 17 are energized by connection 26 relay contact 27 and wire 28 to coils 17 and return conductor 29 to wire 24. 12^a represents a ramp shorter in length than the ramps 12 and energized by coil 17^a in multiple with the coil 17 for the block B, as will be more particularly described in connection with the speed control system. This arrangement is in accordance with the established practice in block signaling.

On the locomotive a battery 31 is provided controlled by the double pole, double throw switch 32, connecting by wires 35 and 36 to a D. C. motor 33 which drives an A. C. generator 34, thereby providing a continuous supply of alternating current on the locomotive.

41 represents the magnetic yoke of a member having a pole piece 42 passing through the vertical plane of pole 15 of the ramp and another pole piece 43 passing through the vertical plane of pole 14 of the ramp. This yoke is provided with a coil 45 and a corresponding yoke is provided on the opposite side having similar reference characters.

The coils 45 are connected in multiple circuit by wires 46 and 47 to the A. C. relay 48 across the terminals of which a condenser 49 is placed.

From this construction it will be apparent that when the magnetic yokes 45 pass over a ramp as shown in Fig. 1 with the coils 17 energized these coils become in effect the primary of a transformer of which the coils 45 are the secondary and thereby an induced current is set up in wires 46 and 47 to energize relay 48. If current is absent from the coils 17, it is apparent that relay 48 will not be energized when these yokes pass over a ramp.

Between the yokes 41 is located the transformer shoe 51 with its poles 52 and 53 at right angles to the poles of yokes 41 and so arranged that these poles engage one plate only of the ramp. Attention is here called to the fact that the pole pieces 52 and 53 are provided with spring contact brushes 44 also indicated in connection with pole pieces 42 and 43. The object of these spring contact brushes is to reduce the reluctance of the circuit by providing a yielding metallic connection between the poles of the shoe and the poles of the ramp. It should be understood, however, that this is not an essential part of the system and that the apparatus is designed to function without making actual contact although its efficiency will be materially increased if this contact is provided.

The transformer shoe has a primary winding connecting to one pole of 34 from wire 61 through coil 56, wire 62 and resistance or reactance 63 to the other terminal of generator 34, thus permanently establishing the circuit of the primary winding. The circuit of secondary winding 57 is established from the common wire 61 through coil 57, wire 64, contact 65 of relay 84, wire 66, contact 67 of indicator 70, wire 69, through indicator coils and wire 71 to the common wire 61. Under normal conditions therefore, indicator 70 is maintained energized by the circuit just described.

It will be noted that between wire 66 and wire 71, energized from the secondary coil 57 of the transformer shoe, the slow releasing relay 75 and the quick releasing relay 76 are connected, these relays being provided in connection with the speed control system.

The transformer shoe is provided with a coil 54 connecting by wire 82 to one side of the battery and by wire 83 through the coils of the safety relay 84 and wire 81 to the opposite side of the battery 31. This sets up a permanently established D.C. circuit through the coils 54 and includes the safety magnet 84 in series. There is thus a tendency to create a magnetic flux through each of the transformer cores 56^a and 57^a. This condition, however, is prevented by the reluctance of the air gap between poles 52 and 53 so that the

flux passing through the transformer cores created by the coils 54, is comparatively small until the transformer shoe engages a plate of a ramp as shown in Fig. 1, when the magnetic reluctance between poles 52 and 53 is greatly reduced, thereby forcing a heavy flux from the coils 54 through the cores 56^a and 57^a of the transformer, bringing these cores up to saturation, thereby for practical purposes, almost eliminating the current from the secondary coil 57 and deenergizing the holding circuit of indicator 70 and the circuits of relays 75 and 76. It should here be noted that the purpose of the safety relay 84 is to guard against a possible open circuit in the coils 54. Should such an open circuit occur, this relay will be deenergized and thereby produce the conditions leading to the operation of the train-control apparatus 20 as will hereinafter be described.

The magnetic yokes 41 are so arranged as to engage a ramp before the transformer shoe 51 and to hold this engagement after the transformer shoe 51 has passed over the ramp. This condition applies whether the locomotive runs front or rear end first. If alternating current is present in the ramp, relay 48 is energized, setting up a circuit from wire 69 through contact 72 to wire 73, resistance coil 63, wire 62 to generator 34 and wire 71 to indicator 70, thereby holding the indicator energized when the secondary coil 57 is deenergized. On the other hand if relay 48 is not energized when the transformer shoe 35 engages the ramp, the stick circuit of indicator 70 becomes deenergized through contact 67, wire 66, contact 65 of relay 84 and wire 64 to the secondary of the transformer shoe, and cannot again become energized until a ramp is encountered energized by alternating current.

Ramps are made of various lengths as indicated at 12 and 12^a, Fig. 3, according to the permissible speed on the track at any particular location. When the secondary of the transformer shoe is deenergized relay 76 is immediately deenergized and relay 75, while it is deenergized is slow releasing, requiring an interval of time to change from the energized to the deenergized position. 98 represents a brake valve or train controlling mechanism which is held energized by the stick relay 86 through wire 97, contact 100, wire 81 to battery and wire 99 from the opposite side of the battery. Stick relay 86 connects on one side to battery wire 82 and on the opposite side by wire 87, contact 91 to wire 92, controlled by contact 93 of relay 76 energized, to battery wire 81. When relay 76, 63 therefore, is deenergized, the stick relay 86 is also deenergized. In order, however, to prevent the brake magnet 98 from becoming deenergized while the transformer shoe is on the ramp, a circuit is established from wire 81 through contact 96 of relay 76 deener-

gized, to wire 97 controlling brake valve 98. Contact 96 is designed to close before contact 93 opens. If the train in passing over a ramp, has not exceeded a predetermined speed, then relay 75 has time to open, closing a circuit from battery wire 81 through contact 89 to wire 87 which picks up stick relay 86 and which thereby remains picked up until relay 76 is again energized thus maintaining the circuit of brake magnet 98. 70 An audible signal device 95 is operated by the back contact 93 of relay 76 through wire 94 and wire 82, thereby indicating that relay 76 is operating for each ramp that is engaged. 75

The usual railroad practice does not require speed control when the track is clear. Therefore, the pick up circuit of relay 86 connects by wire 87 through contact 88 of the indicator 70 energized, to the battery wire 81, thereby holding relay 86 energized, when the track is clear, without regard to the operation of relays 75 and 76. It is usual to release the train-control apparatus after it has become effective in controlling the train so that a train may proceed under caution to the next block. For this purpose, the push button 90 is provided to be manually operated connecting wire 87 with battery wire 81 and thereby energizing relay 86. 80

When the double pole, double throw switch 32 is changed to the opposite position, the entire system is deenergized and the brake valve 98 is maintained energized through connection 101. 90

It has been shown that the transformer shoe in passing over a plate of the ramp has the magnetic reluctance between its poles reduced. This condition would also apply when this shoe passes over the track rails of a turn-out such as is shown at "C" in Fig. 3. This condition, however, does not influence the operation of the transformer shoe to any appreciable extent for the reason that as the poles of the ramp are located on a higher elevation than the head of the rail, there is a very much greater air gap between the head of the rail and the poles 52 and 53, than exists between these poles and the ramp. Also the rails of a turn-out do not run parallel to the running rails of the main track so that the poles of the transformer shoe pass over the rail head obliquely and as the distance separating the pole pieces is much wider than a rail head, conditions do not prevail from this source which would cause a false operation of the 100 system. 110

In the arrangement shown in Figs. 4 and 5, the ramp is provided with three pole pieces, 113, 114 and 115, energized by the magnet coils 111 and 112 through the laminated core 116. The ramp poles can thus be independently energized with different polarities or they may be energized with current differing in phase, as shown in the arrangement in Fig. 5, in which the transformer 188 by means of 125 130

wire 189, contact 190 of track relay 21, wire 191, coils 112, wire 192, contact 193 and impedance 194, energizes one set of coils of the ramp and from wire 191, coil 111, wire 195, 5 contact 196 of relay 181 and wire 197, energizes the other coils of the ramp. As shown, it will be noted that in circuit with the coils 112, is included the impedance 194, causing a phase displacement between the currents 10 energizing the coils 111 and 112. When relay 181 is deenergized then contact 193 connects to the wire 195 and contact 196 connects to wire 192, thereby placing the impedance 194 in circuit with coils 111 and removing it 15 from the circuit of coils 112 and thus changing the phase relation between the two sets of coils. A two phase current could, of course, be used instead of a phase-splitting arrangement as here shown and this phase relation 20 could be obtained from two independent ramps, one for instance, on either side of the track, with the coils connected as shown.

The track arrangement in Fig. 5 is in accordance with a well-known practice in block 25 signaling, in which a train in block A de-energizes relay 21 and thereby deenergizes both sets of coils of the ramp, whereas a train in block B deenergizes controlling relay 181 from wire 187, battery 186, contact 185, wire 30 184, contact 183, wire 182 to relay 181, thus changing about the phase relation in the coils 111 and 112, depending upon whether block B is occupied or unoccupied and deenergizing both of these coils when block A is occupied.

35 The locomotive apparatus consists of a magnetic yoke 41 having three pole pieces 117, 118 and 119, passing through the vertical plane of the ramp poles 113, 114 and 115 respectively. Between the poles 117 and 118 40 the coil 120 is placed connecting by wires 122 and 123 to coil 124 of the poly-phase relay 128 and between the poles 118 and 119, the coil 121 is placed, connecting by wires 125 and 126 with coil 127 of the poly-phase relay 128. 45 This relay has a rotor armature carrying arm 129 with a contact plate as shown. When either or both of coils 124 and 127 are deenergized, this arm assumes the neutral position shown. When the phase relation in one coil 50 differs from another, this arm swings to the side, in one case swinging to the right and making contact with the terminal 130, establishing a circuit from wire 134 of generator 34 through resistance 133 and wire 132 to wire 136 and when swung in the opposite direction, this arm makes contact with a pair 55 of terminals at 131, establishing a circuit from wire 132 to wire 138 and also to wire 136, hereafter referred to. The transformer 60 shoe 51 has pole pieces 52 and 53 passing over plate 115 of the track ramp. This shoe includes a transformer yoke having a primary coil 151 connecting between wires 135 and 134 from the terminals of the A. C. generator 34, so that this circuit is permanently en-

ergized. A secondary winding is provided on the other leg of the transformer, including a pair of independent secondary coils, indicated at 152. One of these coils connects by wire 153 through contact 155, and wire 138 70 to block relay 140. The other coil connects by wire 154 through contact 156, and wire 136 to block relay 139. The block relays connect to common wire 135 which connects to the opposite side of the secondary 75 windings 152. The circuits just mentioned act as holding circuits for the A. C. block relays 139 and 140 and maintain these relays energized until the transformer shoe-passes over a ramp plate as indicated in Fig. 4, when 80 the magnetic flux is diverted from the secondary core of the transformer through the plate of the ramp, thereby reducing the current in the secondary coils 152 and deenergizing relays 139 and 140, and setting up the conditions leading to a stop effect. The air gap 85 152^b in core 152^a assists this condition. 152^b is a break in the magnetic circuit with the object of increasing the reluctance of this circuit. It is common practice to refer to this as an air 90 gap in the circuit, although in the present case, the shading indicates this gap is filled with a non-magnetic material.

110 represents a light type of cab signal having a green or proceed indication, indicated by the letter "G" and controlled by wire 164, contact 163 of relay 140, wire 162, contact 161 of relay 139, to wire 134, thereby giving a green indication when relays 139 and 140 are energized. This signal has another light "Y" giving a caution indication, controlled by wire 169, contact 168 of relay 140, wire 167, contact 165, of relay 139, deenergized, to the energy wire 134, or by contact 168 of relay 140, deenergized, wire 166 and 105 contact 165 of relay 139 energized to energy wire 134, thereby giving a caution signal when either of relays 139 or 140 is energized and the other deenergized. This signal also includes a stop indication, indicated by the letter "R", controlled by wire 173, contact 172 of relay 140, deenergized, wire 171 and contact 170, of relay 139, deenergized, to energy wire 134, thereby giving a stop indication when both relays 139 and 140 are deenergized. This arrangement is more fully explained in United States Patent #1,299,595 and is only shown in the present invention as a convenient means of applying the effects obtained inductively from the track, which may 110 be used for any purpose on the locomotive.

Considering the operation of this system, it will be noted, that if a locomotive engages a track arrangement as shown in Fig. 5, the coils 112 will lag in phase behind the coils 111 with the result that the arm 129 is swung to the left, thereby establishing a pick-up circuit for relays 139 and 140 and maintaining this circuit while the transformer shoe 51 is under the influence of the track ramp. 130

Suppose now, that under the same conditions, block B is occupied and relay 181 is deenergized, then coils 111 will lag in phase behind the coils 112, causing the arm 129 of the poly-phase relay to swing to the right, establishing a pick-up circuit of block relay 139 and failing to establish the pick-up circuit for relay 140 with the result that relay 140 becomes deenergized, due to the transformer shoe coming under the influence of the ramp. This relay remains deenergized until a phase displacement is obtained to swing arm 129 to the left. If now, block A is occupied so that both coils 111 and 112 are deenergized, then the block relays 139 and 140 are deenergized and remain deenergized until a ramp is encountered having the coils 111 and 112 energized as before described. With this arrangement, it will be noted that a variety of effects may be obtained on the locomotive from a track device energized by currents differing in phase and these effects are obtained in a direct and positive manner, by inductive means without the use of permanent magnets of any kind.

The modified arrangements shown in Figs. 6, 6^a and 6^b, include a locomotive shoe with a moving element as a substitute for the transformer shoe, and also include a multiple pole arrangement for providing a path for the direct current flux of the locomotive device through the track device. Another feature included in these arrangements is a detector which, in response to each proceed signal received from the ramp, detects the proper working of the stop effect.

The stop magnet which takes the place of the transformer shoe in the previous illustrations, consists of a magnetic yoke having a coil powerfully energized from a source of direct current on the locomotive. This coil creates a flux which under normal conditions raises an armature and holds it in the raised position until this magnet passes over a ramp when a path of less reluctance is provided for the lines of force and which thereby moves this armature into the opposite position. The armature is raised against gravity for the proceed effect so that if the current is absent the armature will assume the stop position.

The magnetic circuit for the stop magnet just described utilizes the magnetic yokes of the A. C. magnets and takes advantage of the increased number of pole pieces thereby obtained, thus decreasing the reluctance of the magnetic circuit when this magnet comes under the influence of a ramp.

The construction of this arrangement consists in placing the magnetic yoke of the stop magnet at right angles to, and in contact with, the cores of the two A. C. magnets with an armature arranged to move in a vertical plane between these magnets. Connected to this armature is the primary core of a trans-

former which energizes or deenergizes the block relays depending upon the position it takes up.

Referring to the drawings in which corresponding parts of the controlling circuits have similar reference characters to those shown in Fig. 4, 201 is the core of the A. C. magnetic yoke having the pole pieces 202, 203 and 204 aligning with the poles of the three pole ramp as shown in the end elevation in Fig. 6^a. When a two pole ramp is used, an elevation corresponding to Fig. 6^b is provided having the poles aligning as indicated. 205 is the magnetic yoke of the stop magnet having an extension 206 resting upon the core 201. Pivoted to the inner side of this extension at 207 is the horizontal armature 208 upon which the coil 209 is placed and permanently connected to the circuit of battery 31 through wires 81 and 82, thereby energizing the armature 208 with a powerful flux. This establishes a magnetic circuit through the yoke 205 and the pole 210 to the armature 208 through the magnetic insulation 211 and thereby holds the armature 208 in the raised position which establishes conditions for maintaining the block relays 139 and 140 in the proceed position. This is secured by the moving primary 212 of the transformer having a winding 213 connected by wires 134 and 135 to the A. C. generator and inducing a current in the secondary coils 226 on the stationary core 225 supported by the bracket 227. This secondary has a double winding, one side of which connects to wire 153 and maintains the holding circuit for relay 140 and the other winding connects to wire 154 and maintains the holding circuit for relay 139.

When the stop magnet 205 passes over a ramp as indicated in Fig. 6, then another path is provided for the lines of force created by the magnet coil 209 through the core 201 and the pole pieces through the ridges of the ramp to the pole pieces connected with the core 201^a and through the air gap to the armature 208. Owing to the number of pole pieces and the large amount of iron in this circuit the magnetic reluctance is less than through the path 205 and the insulation 211, with the result that the armature 208 assumes the deenergized position moving into contact with the core 201^a during the time that this magnet is under the influence of the ramp. This action it should be noted, takes place quite independently of the A. C. magnet and the current induced in coils 119 and 120 for the operation of the poly-phase relay 128. As soon as this magnet passes over the ramp the reluctance of the magnetic circuit through cores 201 and 201^a is greatly increased and the lines of force pass through the yoke 205 and raise the armature through the yoke 205 to the position shown.

When the armature 208 is deenergized or moves into the lower position the primary

core 212 is moved from alignment with the secondary core 225, thereby deenergizing the secondary circuits and deenergizing relays 139 and 140 without providing moving contacts on the armature for this purpose.

5 The arm 214 moving with the armature 208 carries contact finger 215 connecting to wire 134 from one side of the A. C. generator. When in the position shown in Fig. 6, a circuit is established from wire 134, to wire 216 and to contact 217 of the poly-phase relay 128. When this relay swings to one extreme position a circuit is established between wire 216 and contact 218 and when in the other extreme position a circuit is established to contact 219. Contacts 218 and 219 connect by wire 220 to the indicating device 221, the opposite side of which connects by wire 135 to the A. C. generator. From this arrangement 10 it will be noted that each time the poly-phase relay moves to either extreme position the indicator 221 will be operated if the armature 208 has not changed position. The indicator 221 is, therefore, a detector on the operation 15 of the armature 208; this armature should move to the deenergized position each time a ramp is engaged and the indicator 221 affords a convenient means of showing when the armature 208 fails to operate when passing an 20 energized ramp.

25 The contact finger 215 makes contact with wire 222 when the armature 208 is in the de-energized position. This wire energizes finger 129 moved by the poly-phase relay 128 and connecting with contacts 130 or 131 for the purpose of completing the circuit of block 30 relay 139 when finger 129 moves to the right and completing the circuit of block relay 140 when finger 129 moves to the left from the 35 A. C. supply 34. Thus, it will be noted that the energy for the pick-up circuit of the block 40 relays is obtained only when the stop magnet is in the stop position. This affords an additional means of insuring the proper operation 45 of armature 208 when passing over a ramp. It will readily be understood that the circuit energizing either of the block 50 relays may include the speed control arrangement shown in Fig. 1 in which wire 135 is the equivalent of wire 71 and either of wires 55 153 or 154 is the equivalent of wire 66 and upon the circuit of these wires relays 75 and 60 76 may be operated.

65 When operating on a poly-phase ramp I prefer to place the magnetic yoke 205 in the centre between coils 119 and 120 as shown in Fig. 6^a and when used on a single phase ramp I divide the coil on core 201 into two parts as shown in Fig. 6^b. These parts may be connected in series as shown.

70 The form of my invention described includes certain novel arrangements of apparatus on the train and certain novel constructions on the trackway. To a limited extent 65 the trackway apparatus co-operates with the

70 specific locomotive apparatus shown, but in general, the locomotive apparatus can be applied with a variety of types of trackway apparatus such as will produce the controlling effects on the locomotive apparatus described, 75 also the trackway apparatus may be used to operate other arrangements of locomotive apparatus from that shown, it is to be understood, therefore, that this invention covers a full range of equivalents for the apparatus 80 shown, both on the trackway and on the train.

85 Certain features of my invention divided out of this application are embodied in the co-pending continuing in part application, 80 Serial No. 315,314, filed October 26, 1928.

Having thus described my invention, I claim:

1. In combination, a railway track, a ramp on said track, consisting of a plurality of 85 magnetic ridges placed parallel with said track, a plurality of sets of coils for energizing said ridges and means for energizing said coils by currents differing in phase.

2. In combination, a railway track, a ramp 90 on said track, consisting of three magnetic ridges placed parallel to said track, and an independent set of coils for energizing each pair of said ridges.

3. In combination, a railway track, a ramp 95 on said track consisting of a plurality of magnetic poles, a set of coils placed between each of said poles and means for energizing said coils by currents differing in phase relation.

4. In combination, a railway track, a ramp 100 on said track, consisting of a magnet with three extended poles placed parallel to the track, coils placed between each pair of said poles and means for energizing said coils.

5. In combination, a railway track, a vehicle thereon, a device on said track, consisting of a plurality of magnets, energized by current of different phase relation, a device on said vehicle having a member coacting inductively with said track device, a relay associated with said member and means for operating said relay in response to the phase relation of the current in said track device. 105

6. In combination, a railway track, a vehicle thereon, a device on said track, consisting of a plurality of magnetic poles, a plurality of sets of coils for energizing said poles with current differing in phase relation, a member on said vehicle coacting with said poles and a poly-phase relay operated by said member. 110

7. In combination, a railway track, a vehicle thereon, a device on said track consisting of a plurality of magnetic poles, a set of 115 coils placed between said poles, means for energizing said coils by current differing in phase relation, a member on said vehicle coacting with said track device, said member delivering current differing in phase rela- 120

tion corresponding to the phase difference in said track device.

8. In combination, a railway track, a vehicle thereon, a device on said track, consisting of a plurality of magnets, a set of coils for energizing each of said magnets, means for energizing said coils by current differing in phase relation, a member on said vehicle coacting inductively with the magnets of said track device, a poly-phase relay associated with said member and means for moving said relay in one direction when the phase difference in said track device is in one direction and for moving said relay in the opposite direction when the phase difference in said track device is reversed.

9. In combination, a railway track, a vehicle thereon, a ramp on said track, consisting of a plurality of magnets, a set of coils for energizing each of said magnets with current differing in phase relation, an inductive device on said vehicle coacting with said magnets and a poly-phase relay associated with said device, means whereby said relay assumes a neutral position when the circuit of one of said ramp coils is deenergized and means whereby this relay is moved in a particular direction in response to the phase relation between the coils of said ramp.

10. In combination, a railway track, a vehicle thereon, a ramp on said track, consisting of three magnetic poles, a set of coils placed between said poles and energized by current differing in phase relation, a device on said vehicle having three poles, each pole cooperating with a pole of said track ramp, a coil connected between each pair of poles on said vehicle device, whereby currents differing in phase relation are induced in said coils from the coils of said track ramp.

11. In combination, a railway track, a vehicle thereon, an iron ridge on said track, a magnet on said vehicle having a pivoted armature with an energizing coil, a pair of poles for said magnet, said poles arranged to pass through the vertical plane of said track device whereby when said magnet is energized, said armature is moved on its pivot.

12. In combination, a railway track, a vehicle thereon, an iron ridge on said track, a magnet on said vehicle having a pivoted armature with an energizing coil, a magnetic yoke for said magnet, pole pieces for said magnet arranged to pass through the vertical plane of said ridge, said pole pieces and said track device forming an alternative yoke for said magnet whereby said armature is moved on its pivot.

13. In combination, a railway track, a vehicle thereon, a magnetic device on said track comprising a plurality of magnetic members, a magnet on said vehicle having a pivoted armature and including a magnetic yoke with an air gap, extended pole pieces for said magnet arranged to align with said

magnetic members, the reluctance of the magnetic circuit through said pole pieces and magnetic members being less than the reluctance through said yoke whereby said armature is moved on its pivot.

14. In combination, a railway track, a vehicle thereon, a magnetic device on said track, a magnetic yoke on said vehicle arranged to come under the influence of said track device, circuits on said vehicle associated with said yoke, and means for simultaneously transmitting an inductive effect to and receiving an inductive effect from said track device affecting said circuits.

15. In combination, a railway track, a vehicle thereon, an iron plate on said track, a magnet on said vehicle having a horizontally pivoted armature, a coil for energizing said magnet, a magnetic yoke for said armature on said vehicle and a second magnetic yoke formed by said iron plate, whereby said armature when magnetized is held in the raised position by the magnetic yoke on the vehicle and is moved to the lowered position by the magnetic yoke formed by the iron plate.

16. In combination, a railway track, a vehicle thereon, a magnetic device on said track, a magnet on said vehicle having a horizontally pivoted armature with an energizing coil, a magnetic yoke with an enlarged air gap for said armature, pole pieces for said magnet having an enlarged area, said pole pieces in combination with said track device, forming a magnetic yoke for said armature, alternative to the first mentioned magnetic yoke.

17. In combination, a railway track, a vehicle thereon, a magnetic device on said track, a shoe on said vehicle having poles coacting magnetically with said device, and flexible magnetic brushes secured to said poles, said brushes making contact with said device.

18. In combination, a railway track, a vehicle thereon, a magnetic device on said track, a shoe on said vehicle having poles coacting magnetically with said device and flexible magnetic connections between said poles and said device.

19. In a railway traffic controlling system, the combination of a railway track, a vehicle thereon, an iron plate on said track, a magnet on said vehicle having a horizontally pivoted armature, with an energizing coil, a magnetic yoke for said armature on said vehicle and a second magnetic yoke for said armature formed by said iron plate, means whereby a proceed effect is communicated to said vehicle when said armature responds to the magnetic yoke of said vehicle and a retarding effect is communicated to said vehicle when said armature responds to said iron plate.

20. In combination, a railway track, a vehicle thereon, a device on said track and a device on said vehicle coacting with said track

- device, said vehicle device associated with one element of a transformer whereby the same is moved in response to said track device, the other element of said transformer associated with a translating device.
21. In a railway traffic controlling system, a track, a ramp on said track consisting of a magnetic plate, means for energizing said ramp, a vehicle on said track, a member on said vehicle responding to the energy in said ramp for communicating a proceed signal to said vehicle and a member on said vehicle responding to said magnetic plate for producing a stop effect on said vehicle.
22. In a railway traffic controlling system, a track divided into blocks, a vehicle thereon, a ramp on said track energized by currents of different phase relation, a transformer device on said vehicle responsive to said track device and a poly-phase relay operated by said transformer device.
23. In a railway traffic controlling system, a track divided into blocks, a vehicle thereon, a ramp on said track energized by currents differing in phase relation, said currents controlled by said blocks, a transformer device on said vehicle inductively responsive to said track device, a three position poly-phase relay operated by said transformer device, said relay assuming a neutral position when said track device is deenergized and assuming either of two active positions according to the phase relation of said currents.
24. In a railway traffic controlling system, a track divided into blocks, a vehicle thereon, a device on said track energized by current controlled by said blocks, a mechanism for controlling said vehicle, a transformer device on said vehicle cooperating with said track device to bring said controlling mechanism into operation and means on said vehicle responding to the current in said track device for preventing the operation of said controlling mechanism.
25. In a railway traffic controlling system, a track, a vehicle thereon, a signaling device on said vehicle, a device on said track, a transformer device on said vehicle operated by said track device, a plurality of relays associated with said transformer device and an independent secondary coil on said transformer device for each of said relays controlling said signaling device.
26. In combination, a railway track, a vehicle thereon, a ramp on said track consisting of a plurality of magnetic members, a plurality of magnetic yokes on said vehicle having pole pieces aligning with the magnetic members of said ramp, a magnetic device on said vehicle placed at right angles to said yokes and means whereby said yokes in combination with the magnetic members of said ramp vary the magnetic circuit of said magnetic device.
27. In combination, a railway track, a ve-
- hicle thereon, a ramp on said track consisting of a plurality of magnetic members, a pair of magnetic yokes on said vehicle arranged to align with said magnetic members, a magnetic device on said vehicle connecting said magnetic yokes and means for magnetizing said magnetic device.
28. In combination, a railway track, a vehicle thereon, a ramp on said track consisting of a plurality of magnetic members, a pair of yokes on said vehicle arranged to align with said magnetic members, a coil surrounding each of said yokes, a magnetic device on said vehicle connecting said yokes, means for energizing said magnetic device and means for energizing said coils from said ramp.
29. In combination, a railway track, a vehicle thereon, a ramp on said track consisting of a plurality of magnetic members, a pair of magnetic yokes on said vehicle arranged to align with the magnetic members of said ramp, a device on said vehicle permanently energized by direct current and means whereby the magnetic circuit of said device is diverted through said yokes and the magnetic members of said track ramp.
30. In a railway traffic controlling system, a track divided into blocks, a vehicle thereon, a device on said track controlled by the conditions of said blocks, a device on said vehicle responding through said track device to said block conditions for giving a proceed effect to said vehicle and a device on said vehicle responding inductively to said track device for producing a retarding effect on said vehicle.
31. In combination, a railway track, a vehicle thereon, a ramp on said track consisting of a plurality of magnetic members, a pair of yokes having pole pieces arranged to align with said members, a magnetic device placed transversely to said yokes, a coil on said yokes on each side of said magnetic device, means on said vehicle for energizing said magnetic device and means on the track for energizing said coils.
32. In a railway traffic controlling system, a track divided into blocks, a vehicle thereon, a device on said track having magnetic members controlled by the conditions of said blocks, a device on said vehicle responding to clear track conditions in said track device, a magnetic device on said vehicle responding to the magnetic members of said track device and means whereby clear track conditions are established when said magnetic device responds to said track device.
33. In a railway traffic controlling system, a track divided into blocks, a vehicle thereon, a device on said track controlled by the conditions of said blocks, a device on said vehicle responding to clear track conditions through said track device and another device on said vehicle responding inductively to said track device and means whereby a clear track con-

dition can only be given by the cooperation of both of said devices.

34. In a railway traffic controlling system, a track divided into blocks, a vehicle thereon, 5 a device on said track consisting of magnetic members and controlled by the conditions of said blocks, a device on said vehicle responding inductively to said track device to give a proceed signal and a device on said vehicle 10 responding inductively to said track device to give a stop signal and means whereby the proceed signal can only be obtained by the cooperation of both of said devices.

35. In a railway traffic controlling system, 15 a track divided into blocks, a vehicle thereon, a device on said track consisting of a magnetic member controlled by the conditions of said blocks, a device on said vehicle responding inductively to said track device for registering a proceed signal according to block conditions and a magnetic device on said vehicle responding inductively to said track device to produce a retarding effect on said vehicle and means whereby the operation of the first 25 device will detect the failure of the latter device.

36. In combination, a railway track, a vehicle thereon, a device on said track, and a device on said vehicle, said vehicle device 30 moved by said track device, a transformer on said vehicle having one element rigidly connected with said vehicle device, the other element of said transformer operating a translating device.

35 37. In a railway traffic controlling system, the combination of a railway track, a vehicle thereon, a device on said track controlled by traffic conditions, a magnet on said vehicle having a movable armature with an energizing 40 coil and a magnetic yoke, means for moving said armature into a position to give a proceed signal to said vehicle when energized and means for moving it into a position to give a stop signal to said vehicle when energized and under the influence of said track 45 device.

38. In a railway traffic controlling system, the combination of a railway track, a vehicle thereon, a device on said track controlled by 50 traffic conditions, a magnet on said vehicle having a pivoted armature with an energizing coil, means whereby said armature when energized assumes a position to give a proceed effect to said vehicle and when energized 55 and under the influence of said track device, assumes a position to give a retarding effect to said vehicle and when deenergized, assumes a position to give a retarding effect to said vehicle.

60 39. In combination, a railway track, a vehicle thereon, a magnetic device on said track, a magnetic yoke on said vehicle arranged to come under the influence of said track device, a plurality of circuits associated with said 65 yoke, means for transmitting an inductive

effect to said track device affecting one of said circuits and means for receiving an inductive effect from said track device affecting the other circuit.

40. In combination, a railway track, a vehicle thereon, a magnetic device on said track, a device on said vehicle having a magnetic yoke arranged to come under the influence of said track device, a controlling mechanism on said vehicle, a plurality of circuits associated with said yoke, one of said circuits controlling said mechanism to produce a proceed effect and the other circuit controlling said mechanism to produce a stop effect on said vehicle. 70 75

41. In combination, a railway track, a vehicle thereon, a magnetic device on said track, a device on said vehicle having magnetic yokes arranged to come under the influence of said track device, a translating device on said vehicle, means whereby said yokes receive an effect from said track device to produce a proceed condition in said translating device and means whereby said track device produces a stop condition in said translating 80 85 device through said yokes. 90

42. In combination, a railway track, a vehicle thereon, a magnetic device having a pair of poles on said track, a device on said vehicle having magnetic yokes arranged to form a circuit for the flux between the poles of said track device and to form a circuit for the magnetic flux passing along the poles of said track device and a translating device on said vehicle operated by said yokes. 95 100

43. In combination, a railway track having magnetic devices with a plurality of poles, a vehicle on said track having a controlling mechanism, a device on said vehicle having a plurality of poles co-acting with said track devices and means for independently operating said controlling mechanism by the magnetic flux between the poles of said track devices and by the magnetic flux along the poles of said track devices. 105 110

44. In combination, a track with a vehicle thereon, a block system controlling traffic on said track, a device on said vehicle responsive to said block system, a transformer on said vehicle having primary and secondary elements mounted in movable relation to each other, a translating device on said vehicle connected with one of said elements and the movement of said elements being effected by said vehicle device. 115 120

45. In a railway traffic controlling system, the combination of a track with a vehicle thereon, a block system controlling traffic on said track, a device on said vehicle controlled by said block system to produce a retarding effect on said vehicle and an independent device controlled by said block system to produce a proceed effect on said vehicle, the accomplishment of said proceed effect being 125 130

dependent upon the operation of the device producing the retarding effect.

46. In a railway traffic controlling system, the combination of a track with a vehicle thereon, a block system controlling traffic on said track, a device on said vehicle controlled by said block system and controlling a circuit to produce a proceed effect on said vehicle and an independent device on said vehicle 10 producing a retarding effect on said vehicle and establishing said proceed circuit when in the retarding position.

47. In a railway traffic controlling system, the combination of a track with a vehicle 15 thereon, a block system controlling traffic on said track, a device on said vehicle inductively controlled by said block system, a relay controlled by said device, a translating device having a circuit controlled by said relay to produce a proceed effect on said vehicle and an independent device on said vehicle arranged to produce a retarding effect 20 on said vehicle and controlling the said circuit of said translating device.

48. In a railway traffic controlling system, the combination of a track with a vehicle thereon, a block system controlling traffic on said track, a device on said vehicle controlled by said block system without making physical contact with said track, a relay controlled by said device and having a plurality of energized positions, a translating device responding to the block system controlled by said relay, an indicator independent of said translating device showing when said relay moves to said energized positions and a device on 35 said vehicle arranged to produce a retarding effect on said vehicle and controlling said indicator.

49. In a railway traffic controlling system, the combination of a track with a vehicle thereon, a block system controlling traffic on said track, a device on said vehicle controlled by said block system to produce a proceed 45 effect and an independent device producing a retarding effect on said vehicle, a translating device and means preventing the operation of said translating device to the proceed position, except when the first mentioned device is in the proceed position and the second mentioned device is in the retarding position.

50. In a railway traffic controlling system, a track divided into blocks, a vehicle thereon, a trackway device having a plurality of energizing coils, means controlled by said blocks 55 for energizing each of said coils by alternating currents differing in phase relation, means on said vehicle responding inductively to said coils and a polyphase relay selectively operated by said vehicle means in accordance 60 with the phase relation of the currents energizing said coils.

51. In a railway traffic controlling system, a track divided into blocks, a track relay 65 associated with each of said blocks, a track-

way device having a plurality of energizing coils, a source of alternating current for energizing each of said coils, means controlled by said track relay for varying the phase relation of the currents energizing said coils, a vehicle on said track having devices responding inductively to said coils and a polyphase relay selectively operated by said vehicle devices in accordance with the phase relation of said currents. 70

52. In a railway traffic controlling system, a track divided into blocks, a track relay associated with each of said blocks, a trackway device having a plurality of energizing circuits, a source of alternating current for energizing said circuits, a reactance controlled by said track relay to be included in one or other of said circuits to change the phase relation of the currents in said circuits, a vehicle on said track having devices responding inductively to said circuits and a polyphase relay selectively operated by said vehicle devices in accordance with the phase relation of the currents energizing said circuits. 75

53. In a railway system as described, the combination, a track with a vehicle thereon, a trackway device simultaneously energized by a plurality of circuits, a source of alternating current for energizing said circuits, a reactance coil for changing the relative phase 80 relation of the currents energizing said circuits, means for including said reactance in one or other of said circuits, devices on said vehicle inductively responsive to said circuits and a polyphase relay selectively operated by said vehicle devices in accordance with the phase relation of the currents energizing 85 said circuits. 90

Signed at New York city, in the county of New York and State of New York, this 105 7th day of June A. D. 1921.

JOHN S. HOLLIDAY.
